Des. 203,765
Patented Feb. 15, 1966

203,765

VEHICLE MARKER LAMP

Allen R. Bushnell, Milwaukee, Wis., assignor to J. W. Speaker Corporation, Milwaukee, Wis., a corporation of Illinois

Filed Dec. 31, 1964, Ser. No. 83,250

Term of patent 14 years

(Cl. D48—32)

Fig. 1.

Fig. 2.

Fig. 3.

Fig. 4.

Fig. 5.

Fig. 6.

FIGURE 1 is a front perspective view of a vehicle marker lamp embodying my new design;

FIGURE 2 is a rear perspective view thereof;

FIGURE 3 is a side view thereof;

FIGURE 4 is a front perspective view of a modified form of the vehicle marker lamp;

FIGURE 5 is a rear perspective view of the lamp of FIGURE 4; and

FIGURE 6 is a side view thereof.

The dominant features of my design reside in those portions thereof shown in solid lines.

I claim:

The ornamental design for a vehicle marker lamp, as shown and described.
